UNITED STATES PATENT OFFICE.

GEORGE BALL, OF PHILADELPHIA, PENNSYLVANIA, ASSIGNOR TO WHITING-PATTERSON COMPANY, INCORPORATED, A CORPORATION OF PENNSYLVANIA.

ENVELOP-MACHINE.

1,313,248.

Specification of Letters Patent. Patented Aug. 19, 1919.

Application filed October 24, 1917. Serial No. 198,224.

To all whom it may concern:

Be it known that I, GEORGE BALL, a citizen of the United States, and a resident of the city of Philadelphia, county of Philadelphia, and State of Pennsylvania, have invented certain new and useful Improvements in Envelop-Machines, of which the following is a specification, reference being had to the accompanying drawings.

10 My invention relates to machines adapted for the production of what are commercially known as window envelopes, that is, envelopes having an opening in the face covered by a piece of transparent or translucent paper 15 through which the address on the contents of the envelop may be read, a principal object of my invention being to combine various means and instrumentalities with a machine adapted for the production of ordinary envelopes, so that either ordinary envelopes or window envelopes may be rapidly and efficiently manufactured upon the said machine as desired.

20 My invention further includes all of the 25 various other objects and novel features of construction and arrangement hereinafter more definitely specified and described.

25 For the purpose of carrying out the objects of my invention I provide an ordinary 30 reciprocating envelop machine of suitable construction with certain means and instrumentalities including means for feeding a continuous web of transparent paper, means for severing the web into predetermined 35 lengths to form the individual coverings for the window openings in the envelopes or "patches" as they are known in the art, means for transferring the severed patch from the cutting means to a proper position 40 for application to the envelop blank, and means for suitably gumming the blank around the window opening. To accomplish these and other functions hereinafter more specifically set forth, I may employ any 45 means and instrumentalities suitable for effecting the results desired, and I do not, therefore, limit myself specifically to those means and instrumentalities which I have herein illustrated and described for the purpose of enabling persons skilled in the art 50 to make, construct and use my invention.

55 For the purposes of this application I have shown my invention as applied to a well-known form of reciprocating envelop machine primarily comprising means for sup-

porting the envelop blank, means for gumming the blank on the back and seal flaps; means for feeding the gummed blanks to a creasing plate, a vertically reciprocating creasing plunger, and means for folding the 60 gummed blanks into completed envelopes, all of these operations and the means generally employed to effect them being familiar to those skilled in the art, and I have, therefore, illustrated somewhat diagrammatically only 65 those portions of the envelop machine necessary to a clear understanding of my invention.

70 In the drawings accompanying and forming a part of this specification, Figure 1 is a side elevation of my invention in combination with a reciprocating envelop machine as aforesaid, certain parts being broken away and other parts being shown in vertical section for the sake of clearness, 75 and Fig. 2 a similar view, certain of the parts, however, being shown in different positions than as shown in Fig. 1. Fig. 3 is a fragmentary view in elevation, and also partially in vertical section, of certain details of my invention, portions of the envelop machine proper being also shown; Fig. 4, a fragmentary view in side elevation of certain details of the mechanism; Fig. 5, a similar view, partially in section, of 80 other details thereof, and Fig. 6 a fragmentary top plan view taken on a plane normal to the plane in which the cutting knife is arranged to reciprocate, as hereinafter described. 90

95 Referring now to the drawings, the envelop machine therein shown comprises the usual frame 1 supporting a bed 2 adjacent the forward end of which (that is, the end toward the left hand side of the sheet in Figs. 1 and 2) is the usual elevator 3 which serves to support a stack of envelop blanks 4 beneath the vertically reciprocating gumming dies 5 which are actuated by suitable mechanism in the ordinary manner, the dies 100 being arranged to descend upon the topmost blank in the stack and deposit a layer of gum upon the flaps of the blank, and also, by means of an additional gumming die 6, around the window opening in the blank, it 105 being understood of course that this opening has been formed in the blank prior to its introduction into the machine. The machine also comprises a stripping plate 7 which serves to strip the blank from the dies as 110

it is carried upward during the reverse stroke of the latter, and a reciprocating carriage 8 which serves to transfer the gummed blank from beneath the stripping plate to 5 a position on a creasing plate 9 beneath a vertically reciprocating creasing plunger 10, which operates to drive the blank downwardly through the creasing plate to the folding bed 12 where the flaps are folded 10 and pressed down into position by suitably actuated folding fingers 13 in the well-known manner. Mechanism (not shown) may also be provided for transferring the completed envelop from the folding bed to a 15 suitable drier from which it is removed after a predetermined period of time, all of these operations and the means ordinarily employed to effect them being well known to, and thoroughly understood by, those 20 skilled in the art.

For the purpose of adapting an envelop machine substantially of the type hereinbefore described for the rapid and economical production of window envelops, I provide and combine therewith various means and instrumentalities, a preferred embodiment of which will now be described and which may comprise a pair of rearwardly and upwardly extending brackets 20 firmly 25 secured to the bed 2 of the machine by bolts 21, these brackets serving to support a reel 23 adapted to carry a roll of transparent or translucent paper 25 preferably of a width sufficient to form a patch of the length desired. I also provide a pair of suitable feed rolls 26 and 27, the latter being stationarily journaled in brackets 20 and the former being supported on a pair of swinging arms 28 and pressed toward roller 27 by a spring 30 29, thereby affording an intimate contact of the rolls with paper 25 when passed between them and insuring a positive feed thereof when the rolls are revolved. For the purpose of intermittently revolving the feed 35 rolls I provide the rolls with suitable intermeshing gears and arrange for the actuation thereof through a suitable gear 30, preferably mounted on the exterior of one of the brackets 20 and carrying a ratchet wheel 31 controlled by a spring pressed pawl 32, in turn actuated by a pair of pivoted bell crank 40 levers 33 and 34 connected by a link 35. The bell crank lever 34 carries a cam roll 36 maintained, as by a spring 37, against a cam 38 positioned on a transversely extending main cam shaft 39 journaled in suitable brackets 40 secured to the bed of the machine and extending rearwardly therefrom, said shaft being driven in any suitable manner as by a chain 41 passing over a sprocket 42 on shaft 39 and actuated from a sprocket on the main driving shaft of the machine. If desired, provision may be made, as by means of a slot 43, for the adjustment of 45 one end of link 35 with respect to one arm

of the bell crank lever 34 thus affording means for regulating the length of the stroke of pawl 32 and, correspondingly, the amount which feed rolls 26 and 27 will be rotated by each revolution of cam 37, thus determining, 70 within limits, the length of paper 25 which will be fed forward at each actuation of the rolls.

Extending transversely between brackets 20 and in front of the feed rolls is a stationary table 44 having a slot 45 adapted to receive the lower extremity of a suitable reciprocating cutting knife 46, as herein-after more specifically described, the table being preferably arranged so that its upper 80 surface will form an angle of about 45 degrees with the horizontal and the knife being normal, or substantially normal, to the plate. For holding the paper 25 in contact with the table during the cutting operation, suitable means are provided which, in the form of the invention shown, comprise a presser foot 48 arranged above the table in front of the knife and loosely carried by a member 50 integral with, or fixedly attached to, a block 51 arranged for reciprocation in a plane substantially parallel to the knife in suitable guideways 53 formed in brackets 20, a keeper plate 56 at each end of the block and spanning the guideways 95 on the exterior of each bracket serving to prevent the lateral movement of the block. The presser foot 48 may preferably be supported from member 50 by suitable studs 60 passing freely through the member, small 100 springs 61 interposed between the presser foot and the member being arranged to hold the parts in separated relation and insuring a good contact between the presser foot and the paper 25 when the former is brought 105 down against the latter to hold it in position on the table. It will be understood that, as best shown in Fig. 1, member 50 is spaced from block 51 for a distance just sufficient to provide a space to contain knife 46 and 110 to permit its reciprocation therein relative to the block and member, which parts are joined together above the upper edge of the knife in such manner that they will move in 115 unitary relation when the block is reciprocated with relation to the plate. For the purpose of reciprocating block 51 and member 50, suitable means are provided, preferably comprising a curved arm 65 disposed outside of each of the brackets 20, the arms being connected by a shaft 66 journaled in and passing transversely through the brackets. The outer end of each arm is movably connected by means of a link 67 with each 120 end of block 51, and intermediate the ends 125 of one of the arms, for example, that on the right hand side of the machine when viewed from the front, is connected a push rod 68 carrying a cam roll 69 bearing on a suitably formed cam 70 positioned on cam shaft 39, 130

a suitably disposed spring 73 on each side of the machine, connected at one end to the arm and at the other to some convenient part stationary with regard to brackets 20, being 5 arranged to constantly draw the curved arms, and in turn block 51, downwardly and insuring continuous contact between the cam roll and the face of the cam.

For the purpose of actuating knife 46, 10 a lever 75 is rigidly secured at one end to a shaft 76 extending transversely of, and journaled in, brackets 20, and at the other end to the knife blade, or to an extension 77 thereof, by links 78, and a suitable push 15 rod 79 carrying at its lower end a cam roll 80 is movably secured at its upper end to a crank arm 76' fixed to one end of shaft 76, the cam roll being arranged to traverse the face of a suitable cam 82 secured on 20 main cam shaft 39, a spring 85 secured at one end to the crank arm and at the other to bracket 20 serving to constantly draw the crank arm downwardly and insure the contact of the cam roll with the cam. It 25 will be understood that each of the push rods 68 and 79 is preferably provided adjacent its lower end with a suitable fork (not shown) arranged to ride over the cam shaft 39 to maintain the cam rolls in correct 30 relation with regard to the cams and prevent their lateral displacement, or if desired, any other suitable means adapted for accomplishing this result may be employed.

Means are provided for transferring the 35 patch after it has been severed from the continuous web 25 by the operation of the knife, as hereinafter described, to the gummed envelop blank positioned beneath the creasing plunger 10, said means preferably comprising a suitable patch conveyer, 40 means for moving the conveyer from adjacent the table to a position beneath the creasing plunger, and means for causing the patch to adhere to the conveyer during 45 this movement. More specifically said means may comprise a yoke shaped conveyer 100, best shown in Fig. 3, the distance between the arms of the yoke being preferably somewhat less than the length 50 of a patch A, which of course is equal to the width of the web 25, the arms of the yoke being preferably rectangular or substantially rectangular in cross section. The conveyer is provided with an upwardly projecting stem 101 rigidly connected with a flanged block 102 arranged for longitudinal reciprocation in a swinging housing 105 provided with a slot 106 in which the block is arranged to engage and which forms a 55 guide therefor, a keeper plate 107 secured to the block and projecting over the edges of the slot on one side of the housing and the flange on the block projecting over the edges of the slot on the other side of the 60 housing serving to prevent the lateral dis-

placement of the block, while a rod 109 extending above and below the block and slidable in suitable longitudinally extending apertures in the housing serves as an additional guiding means to preserve the 70 proper alignment of the block and the housing. The housing adjacent its upper extremity is rigidly secured to, and therefore rotatable with, a transversely extending shaft 112 journaled in a suitable bracket 75 113 secured to the frame of the machine and carrying, adjacent its outer extremity, a crank 114 connected by a link 115 with one end of a bell crank lever 116 pivoted on a shaft 118 journaled in the brackets 40, and 80 having at its opposite end a cam roll 120 arranged for engagement with the face of a cam 121 on cam shaft 39, a spring 122 attached to the bell crank lever and to some suitable portion of the frame of the machine serving to constantly maintain the cam roll and cam in contact. It will thus be evident that any movement of the bell crank lever due to the rotation of cam 121 will result in a movement of crank 114 and 90 partial rotation of shaft 112, thereby imparting to housing 105, and in turn to conveyer 100, a swinging movement about the axis of shaft 112 as a center, the extent of which is primarily determined by the configuration of the face of cam 121 and relative proportions of the arms of bell crank lever 116.

For the purpose of causing the conveyer to assume the proper positions for removing the patch from table 44 and delivering it beneath the creasing plunger, means are provided for effecting a relative movement between the conveyer and the housing, comprising, in the form of the invention shown, 105 a member 130 having a curved slot 131 adapted to receive a roller 132 carried by block 102, as best shown in Fig. 3, the member being pivoted to the frame of the machine upon a stud 134 and connected 110 through a suitable link 135 with one arm of the bell crank lever 136, in turn pivoted on shaft 118 and having adjacent the outer end of its opposite arm a cam roller 139 engaging a suitable cam 140 on main cam 115 shaft 39, a spring 141 connected to the bell crank lever and to some suitable part of the frame of the machine serving to maintain the cam roller and cam in constant contact, so that the rotation of the cam will 120 effect a movement of member 130 about stud 134 in turn effecting a movement of block 102 in housing 105 and a resulting movement of conveyer 100 for a purpose to be hereinafter described.

Means are also provided to cause the patch to adhere to the conveyer during the movement of the latter from a position adjacent table 44 to a position adjacent the envelop blank to which the patch is to be 130

applied, and for this purpose the conveyer is provided with one or more internal apertures or passages 150 terminating at the extremities of the conveyer and communicating through flexible piping 152 with a vacuum pump which may comprise a cylinder 155 open at one end and having a piston 156 actuated through a bell crank lever 157 pivoted to the frame of the machine and 5 operated through a link 158 from a suitable cam (not shown) although, if desired, the pump may be of any other preferred construction. Means are also provided, as best shown in Fig. 5, for releasing the vacuum 10 in the pump, and in turn in the conveyer, at the proper point in the cycle or operations of the machine; for example, a valve 160 operative to close a port 161 in cylinder 155 and actuated through a suitable link 162 15 by means of a bell crank lever 163 pivoted to one of the brackets 40 and carrying a cam roll 164 maintained in contact with a suitable cam 165 on main cam shaft 39 by a suitably positioned spring 168, the cam being 20 adapted to raise valve 160 against the tension of spring 168 to open port 161 and release the vacuum in the cylinder at the proper point in the cycle of operations as 25 hereinafter described.

30 In order to permit the conveyer to bring the patch into proper registration with the window opening in the envelop blank, the creasing plunger 10 is provided with a pair of suitably disposed slots 170 of sufficient size to receive the arms of the conveyer so 35 that it can assume a position substantially parallel to the plunger shaft, and to enable the conveyer to engage the paper beneath presser foot 48 on table 44, the former, as 40 well as that portion of member 50 above the presser foot and lying in the path of the conveyer, is also provided with similar slots 172, as best shown in Fig. 6.

45 The parts having been constructed and assembled in connection with a suitable envelop machine preferably substantially as described, the operation of forming an outlook or window envelop may be briefly indicated as follows: Presuming the parts to 50 be in substantially the position shown in Fig. 1 in which an envelop blank B is being raised from stack 4 through the operation of the gumming dies, and web 25 is being fed forwardly over table 44 through the 55 operation of the feed rolls, the continued rotation of shaft 39 first causes cam 121 to actuate bell crank lever 116 to swing housing 105, and in turn conveyer 100, rearwardly toward table 44, member 130 remaining 60 substantially stationary until the housing has completed about two-thirds of its rearward swing, when, through the actuation of bell crank lever 136 under the influence of cam 140, the extremity of curved member 130 is depressed, thus forcing the

conveyer radially outwardly with respect to the housing to cause it to register with that portion of web 25 which has been fed past slot 45 in table 44, and which is now held in position thereon by presser foot 48 70 which is timed to descend upon the web after the completion of its forward movement under the action of the feed rolls and at a very short interval of time before, or substantially simultaneously with, the descent of the conveyer upon the web, it being understood that the movement of the presser foot is effected through the operation of cam 70, push rod 68, curved arms 65 and links 67, which as hitherto described, are 75 operative to effect the actuation of the block 51 and in turn of the presser foot. The projecting portion of the web which is to form the patch, and the width of which has been determined by the adjustment of link 35 80 with respect to bell crank 34 now being securely held on the table by the action of the presser foot, knife 46 is caused to descend through the actuation of its controlling mechanism by the cam 82 and sever the 85 patch, (the relative position of the parts after this operation being shown in Fig. 2) and substantially simultaneously with this operation, a vacuum is formed within cylinder 155 and in turn within the conveyer, 90 thus causing the severed patch to adhere to the latter. The continued rotation of shaft 39 now brings the cams 70 and 82 into positions to respectively raise the knife and the presser foot and thereafter to swing the 95 outer extremity of member 130 upwardly under the influence of cam 140 to raise the conveyer with its adhering patch away from table 44 sufficiently to permit the patch to clear the table during the forward swing 100 of the conveyer which now commences and which is effected by the action of cam 121 whose continued rotation lifts the outer end of bell crank lever 116 to swing the housing 105 forwardly to assume a position parallel with the creasing plunger shaft, thus bringing the patch into proper alignment with the outlook window opening in the gummed envelop blank B which has meanwhile been 110 stripped from the gumming dies and transferred by conveyer 8 to a position on the creasing plate beneath the creasing plunger. Simultaneously with the termination of the forward swing of the conveyer, member 130 is caused to swing slightly downwardly 115 thereby lowering the conveyer vertically toward the blank, the vacuum in the conveyer being simultaneously released under action of cam 165 to free the patch from the conveyer. Meanwhile, the creasing plunger having begun to descend from its uppermost 120 position prior to the time when the conveyer reached the termination of its forward swing, has now descended sufficiently to contact with the patch and force it and the 125 130

envelop blank simultaneously downward through the folding box to the folding bed, upon which the operations of folding the flaps into final position and firmly pressing 5 the patch in place on the blank are performed by the folding fingers after the plunger has been withdrawn sufficiently to permit them to function. Meanwhile, and during the descent of the plunger into the 10 folding box, member 130, under the influence of its actuating cam 140, has been swung upwardly sufficiently to raise the lower end of the conveyer to a position substantially similar to that shown in Fig. 1 in which the 15 lower ends of the conveyer are entirely clear of the creasing plate and the feed rolls have been again set in operation to feed another length of the patch paper forwardly beneath the knife thus completing the cycle 20 of operations of the machine.

It will thus be evident that through the employment of my invention in connection with an envelop machine, the manufacture of window envelopes may be carried on 25 rapidly and economically, and that, when desired, the same machine may be utilized for the manufacture of ordinary envelopes without in any way disarranging or even changing the adjustment of any of the parts 30 other than detaching the auxiliary gumming die 6 and removing the roll of transparent paper from reel 23, although, of course, it is preferable when utilizing the machine for the manufacture of ordinary envelopes to disconnect chain 42 or other means 35 by which shaft 39 is driven and thereby save unnecessary wear upon the parts actuated through the rotation of this shaft.

While I have herein illustrated and described with considerable particularity a preferred embodiment of my invention and have shown the same in connection with a well-known form of reciprocating envelop machine, I do not thereby desire or intend 45 to limit myself specifically to such embodiment of my invention, or to its use in connection with an envelop machine identical with that to which I have referred, as suitable changes and modifications may be made 50 in the details and arrangement of the various means and instrumentalities employed, and the invention may be adapted for use in connection with other forms of envelop machines, without departing from the spirit 55 and scope of the invention as defined in the appended claims.

Having thus described my invention I claim and desire to protect by Letters Patent of the United States:

60 1. The combination with an envelop machine having means for supporting an envelop blank, means for gumming said blank on the back and seal flaps and around an opening therein, means for feeding the 65 gummed blank to a position beneath a creas-

ing plunger and means for folding the gummed blank into a completed envelop, of paper feeding means, means for severing said paper, and angularly and radially movable means operative in its radial movement 70 to lift a severed portion of said paper from said severing means and in its angular movement to convey said severed portion of said paper from a point adjacent said severing means to a position adjacent said envelop 75 blank beneath said creasing plunger.

2. The combination with an envelop machine having means for supporting an envelop blank, means for gumming said blank on the back and seal flaps and around an opening therein, means for feeding the gummed blank to a position beneath a creasing plunger and means for folding the gummed blank into a completed envelop, of means for intermittently feeding a continu- 80 85 90 95 100 105 110 115 120 125 130

ous web of paper, means for severing said web and angularly and radially movable means operative in its radial movement to lift a severed portion of said paper from said severing means and in its angular movement to convey said severed portion of said paper from a point adjacent said severing means to a position adjacent an envelop blank beneath said creasing plunger.

3. The combination with an envelop machine having means for supporting an envelop blank, means for gumming said blank on the back and seal flaps and around an opening therein, means for feeding the gummed blank to a position beneath a creasing plunger and means for folding the gummed blank into a completed envelop, of means for intermittently feeding a continu- 95 100 105 110 115 120 125 130

ous web of paper, means for severing said web to form a patch and depending means rotatable and slid able in a vertical plane operative in its sliding movement to lift the severed portion of said paper from said severing means and in its rotating movement to convey said patch from a point beneath said severing means to a point beneath said creasing plunger adjacent said envelop blank.

4. The combination with an envelop machine having means for supporting an envelop blank, means for gumming said blank on the back and seal flaps and around an opening therein, means for feeding the gummed blank to a position beneath a creasing plunger and means for folding the gummed blank into a completed envelop, of means operative to intermittently feed a continuous web of paper, means operative to sever said web at a predetermined point to form a patch and means movable about a stationary horizontal axis and also radially with respect to said axis, operative to convey said patch from adjacent said severing means to a position adjacent said blank beneath said plunger.

5. The combination with an envelop machine having means for supporting an envelop blank, means for gumming said blank on the back and seal flaps and around an opening therein, means for feeding the gummed blank to a position beneath a creasing plunger and means for folding the gummed blank into a completed envelop, of means operative to intermittently feed a 10 continuous web of paper, a reciprocating knife operative to sever said web into predetermined lengths to form patches, a patch conveyer, means operative to cause the severed patch to adhere to said conveyer, means 15 operative to impart to said conveyer a swinging movement about a stationary horizontal axis and means operative to impart to said conveyer a radial movement normal to said axis.
- 20 6. The combination with an envelop machine having means for supporting an envelop blank, means for gumming said blank on the back and seal flaps and around an opening therein, means for feeding the 25 gummed blank to a position beneath a creasing plunger and means for folding the gummed blank into a completed envelop, of means for intermittently feeding a continuous web of paper across a table, a reciprocating 30 knife operative to sever said web upon said table to form a patch, a patch conveyer, means for causing said patch to adhere to said conveyer, means for imparting to said conveyer a swinging movement 35 in a vertical plane about a horizontal axis and means for imparting to said conveyer a radial movement with respect to said axis when said conveyer is adjacent said table.
7. In an envelop machine, the combination 40 with means for supporting an envelop blank, means for gumming said blank on its back and seal flaps and around an opening therein, means for transferring said blank from said gumming means to a creasing 45 plate, a vertical reciprocating creasing plunger, and means for folding the blank into a completed envelop, of means for intermittently feeding a continuous web of paper, means operative to sever said paper 50 to form a patch, a swinging patch conveyer, means operative to cause a vacuum within said conveyer during a predetermined interval of time and means operative to impart to said conveyer a radial movement 55 with respect to the axis about which said conveyer is arranged to rotate to cause said conveyer to contact with said patch substantially coincident with the termination of its swing in one direction and to carry 60 said patch to said envelop blank substantially coincident with the termination of its swing in the other direction.
8. In an envelop machine, the combination 65 with means for supporting an envelop blank, means for gumming said blank on its back and seal flaps and around an opening therein, means for transferring said blank from said gumming means to a creasing plate, a vertical reciprocating creasing plunger, and means for folding the blank into a completed envelop, of means for intermittently feeding a continuous web of paper, means operative to sever said paper to form a patch of predetermined width, a patch conveyer movable about a fixed horizontal axis, means to cause said patch to adhere to said conveyer during a predetermined interval of time, means operative to permit said conveyer to move into alignment with said creasing plunger and means for 70 imparting to said conveyer a reciprocating movement in a direction substantially parallel to the axis of said creasing plunger shaft. 75
9. In an envelop machine, the combination with means for supporting an envelop blank, means for gumming said blank on its back and seal flaps and around an opening therein, means for transferring said blank from said gumming means to a creasing plate, a vertical reciprocating 80 creasing plunger, and means for folding the blank into a completed envelop, of means for feeding a continuous web of paper across a table, means to position said web upon said table, cutting means operative to sever said web to form a patch of predetermined width, a patch conveyer arranged for movement about a stationary horizontal axis, means operative to move said conveyer about said axis, means to cause 85 said patch to adhere to said conveyer during its movement in one direction, and means to reciprocate said conveyer in a direction normal to its axis of rotation to bring said conveyer into contact with said patch on said table at the limit of its swinging movement in one direction and to move said conveyer vertically toward said envelop blank at the extremity of its swing in the other direction. 90
10. In an envelop machine, the combination of a housing movable about a fixed axis, a patch conveyer carried by said housing and movable relatively thereto, means operative to move said housing, means for feeding a web of the paper, means operative to support said web, means operative to sever said web to form a patch, a movable member operative to position said conveyer with respect to said housing and said support to contact said patch, and means operative to cause the movement of said member. 105
11. In an envelop machine, the combination of a swinging housing, means operative to swing said housing, a patch conveyer movable with said housing and relatively movable with respect thereto, web feeding means, a web support, means to position the web upon said support, a cutting knife 110
- 120
- 125
- 130

operative to support said web to form a patch and means comprising a pivoted slotted member operative to effect the movement of said conveyer with respect to said housing and said supporting means at predetermined periods with relation to the movement of said housing.

12. In an envelop machine, the combination of a swinging housing, a conveyer movable with and with respect to said housing, means for feeding a web of paper, means operative to support said web, means operative to sever said web to form a patch, means to effect the movement of said housing toward and away from said supporting means, and means operative to move said conveyer with respect to said housing to cause said conveyer to contact with said patch upon said supporting means.

13. In an envelop machine, the combination of a swinging housing, a conveyer movable with and with respect to said housing, paper feeding means, a paper support, means to position the paper upon said support, a cutting knife operative to sever said paper to form a patch, means operative to swing said housing toward and away from said support, means operative to effect a relative movement of said conveyer and said housing to bring said conveyer into contact with the paper on said support, and means to cause said paper to adhere to said conveyer.

In witness whereof, I have hereunto set my hand this 23rd day of October, A. D. 35 1917.

GEORGE BALL.
